(57) **CLAIM**

The ornamental design for a telescoping stock for a submachine gun, as shown and described.

DESCRIPTION

FIG. 1 is a left elevation view of a telescoping stock for a submachine gun showing the design;
FIG. 2 is a right elevation view thereof;
FIG. 3 is a rear elevation view thereof;
FIG. 4 is a front elevation view thereof;
FIG. 5 is a top plan view thereof;
FIG. 6 is a bottom plan view thereof;
FIG. 7 is a front perspective view thereof;
FIG. 8 is a left elevation view thereof, shown in an alternate position;
FIG. 9 is a right elevation view thereof, shown in the alternate position;
FIG. 10 is a rear elevation view thereof, shown in the alternate position;
FIG. 11 is a front elevation view thereof, shown in the alternate position;
FIG. 12 is a top plan view thereof, shown in the alternate position;
FIG. 13 is a bottom plan view thereof, shown in the alternate position; and,
FIG. 14 is a front perspective view thereof, shown in the alternate position.
Broken lines in the drawings are for the purpose of illustrating environmental structure and form no part of the claimed design.

1 Claim, 10 Drawing Sheets
